Primary Examiner — Ian Simmons*Assistant Examiner* — Shannon Morgan(74) *Attorney, Agent, or Firm* — Haugen Law Firm PLLP(57) **CLAIM**

The ornamental design for a pod carousel, as shown and described.

DESCRIPTION

FIG. 1 is a perspective view of a pod carousel showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The portions of the pod carousel shown in broken lines in FIG. 2–5 and FIG. 7 form no part of the claimed design.
